CLAIM

The ornamental design for a shoe outsole, as shown and described.

DESCRIPTION

FIG. 1 is a front perspective view of a shoe outsole showing my new design;

FIG. 2 is a bottom view thereof; and,

FIG. 3 is a rear perspective view thereof.

The broken line showing of the remainder of the shoe represents unclaimed subject matter and forms no part of the claimed design.

1 Claim, 3 Drawing Sheets(56)
